UNITED STATES PATENT OFFICE.

LE ROY P. HOLLOWAY, OF AKRON, OHIO, ASSIGNOR TO THE AMERICAN RUBBER & TIRE CO., OF AKRON, OHIO, A CORPORATION OF OHIO.

DESIGN FOR A TIRE TREAD.

Application filed December 9, 1922. Serial No. 4,561. Term of patent 14 years.

To all whom it may concern:

Be it known that I, LE ROY P. HOLLOWAY, a citizen of the United States of America, residing at Akron, in the county of Summit and State of Ohio, have invented a new, original, and ornamental Design for a Tire Tread, of which the following is a specification, reference being had to the accompanying drawing, forming a part hereof.

I claim:

The ornamental design for a tire tread, as shown.

LE ROY P. HOLLOWAY. [L.S.]
